UNITED STATES PATENT OFFICE.

ALFRED PLANT, OF NEW YORK, N. Y., ASSIGNOR OF ONE-HALF TO FRANK W. SILKMAN, OF SAME PLACE.

FLOOR AND WALL TILE.

SPECIFICATION forming part of Letters Patent No. 659,453, dated October 9, 1900.

Application filed May 25, 1900. Serial No. 17,968. (No model.)

To all whom it may concern:

Be it known that I, ALFRED PLANT, a citizen of the United States, residing at New York, in the county of New York and State of New York, have invented certain new and useful Improvements in Floor and Wall Tiles; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to ornamental tiles for floors and walls. Such tiles are usually made with several shallow grooves in the back, but these grooves have no positive hold on the cement in which the tile is set, merely affording a larger adhesive surface between the tile and the cement. It has been proposed to make these grooves undercut or dovetail in cross-section, so as to afford a key with the cement and give the tile a strong and positive hold thereon; but such undercut grooves are difficult to make, and their thin sharp edges are very liable to become broken off, thereby destroying their holding effect. To remedy this, it has been proposed to make one or more undercut recesses or sockets in place of the grooves; but in pressing such a tile into the cement the air imprisoned in the recess prevents the cement from entirely filling the recess, and thus impairs the completeness and efficiency of the key. My invention aims to overcome these difficulties by providing the tile with a concealed recess having undercut walls and intersected by transverse grooves running out to the edges of the tile, one or more of the grooves being deep enough to afford a free escape for the air in the recess when the tile is pressed into the cement.

In the drawings, Figure 1 is a perspective view of a tile embodying my invention. Fig. 2 is a bottom plan view of the same. Figs. 3 and 4 are cross-sections on the lines 3 3, 4 4, Fig. 2, respectively. Figs. 5 and 6 show different forms of formers for making the concealed recess. Fig. 7 is a perspective view of a modified construction of tile embodying my invention. Fig. 8 is a perspective view show-

ing the bottom of said modification. Figs. 9 and 10 are cross-sections on the lines 9 9, 10 10, Fig. 8, respectively. Fig. 11 shows the former used in making the concealed recess 55 in this modification.

The tile A (shown in Figs. 1 to 4, inclusive) may be of any desired outline or size. In its under side is a cavity or recess B, the shape of which is preferably circular, as shown. 60 The lower portion b of the walls of the recess is upright, but the upper part b' is sloped outwardly or undercut, so as to make the recess larger at the top than at the bottom. The recess is intersected transversely by grooves C, 65 running across the bottom of the tile and out to the sides thereof. These grooves are rather shallow at their outer ends, but preferably increase in depth as they approach the recess until they are of the same depth there as 70 at their points of intersection therewith, as clearly shown in Fig. 3. It will be seen that those portions b of the walls of the recess which lie between the grooves C are comparatively thick, so as to have considerable 75 strength. When such a tile as this is pressed into the cement, the recess will be filled with the plastic cement, and the air in the recess can escape through the grooves C at each side of the tile or at one side in case one edge of the 80 tile enters the cement before the other. In many cases the tile-setter before placing the tile in position applies a dab of cement to it, which enters the recess and expels the air therefrom and afterward forms a firm bond 85 with the body of cement into which the tile is laid. In every case the cement engages with the wider upper part of the recess, and thereby makes a strong key which holds the tile firmly in place. 90

In the modification shown in Figs. 7 to 11 the tile has two rather deep channels D running across its bottom face, with a shallower channel D' lying between them. These channels have sloping sides d and flat tops d' 95 and serve to present a greater surface for the adhesion of the cement. They differ from the ordinary grooves made for this purpose in that they are but three in number and are much deeper and broader. The key-forming recess B' runs from one channel D to the other, crossing the channel D'. The recess 100

has walls which are upright at their lower part b^2 and slope outwardly at their upper part b^3 , thus making the upper portion of the recess larger than the lower portion. This 5 enlarged chamber or cavity affords ample opportunity for the cement to enter and make a strong key with the tile. The grooves C D D' are formed by ribs on the lower die of the tile-press. The recesses are made by 10 placing on said die a former of combustible material. The tile-forming material is then deposited upon and around said former and the tile is pressed, embedding the former within it. When the tile is fired, the former 15 will slowly char and volatilize at the high temperature to which the tile is subjected, thus leaving the recess clear and free from debris.

The formers E E' E² must be made of some 20 material which will not burn with a fierce flame or intense heat, since otherwise they would crack and ruin the tile. It is essential also that this material shall be non-absorbent of moisture, since otherwise it would 25 soak up moisture from the damp clay or dust and by its swelling would burst the tile. The former shown in Fig. 5 is to be placed on a cylindrical support integral with or attached to the die of the tile-press and located at 30 the intersection of the ribs which form the grooves. The former shown in Fig. 6 is to be located at the same place in the die, but its lower cylindrical portion e takes the place

of the support used with the other former. In each case the shape of the recess is the same—that is, it has a cylindrical lower portion and an enlarged flaring upper portion.

Having thus described my invention, what I claim is—

1. A floor and wall tile, having in its under 40 side a recess with undercut walls, and grooves intersecting said recess and running to the sides of the tile.

2. A floor and wall tile, having in its under 45 side a recess with undercut walls, and grooves intersecting said recess, one or more of which are as deep as the recess at the point where they intersect it.

3. A floor and wall tile, having in its under 50 side a recess with undercut walls, and grooves intersecting said recess, which are deeper at the inner end than at the outer.

4. A floor and wall tile, having in its under 55 side a recess with undercut walls, and grooves running from said recess to the sides of the tile, said recess having the lower portion of its walls upright and the upper portion sloping outwardly to form an enlargement of the recess at its upper part.

In testimony whereof I affix my signature 60 in presence of two witnesses.

ALFRED PLANT.
